UNITED STATES PATENT OFFICE

EDWARD J. FORD, OF SPOKANE, WASHINGTON

PNEUMATIC HEADGEAR

Application filed January 7, 1931. Serial No. 507,276.

This invention relates to improvements in helmets for football players and the like and has for the primary object, the provision of a device of the above stated character which 5 will afford efficient protection to the top of the head, forehead, temples and the base of the skull of the player and which will be comfortable and light in weight and capable of withstanding undue wear.

10 Another object of this invention is the provision of a pneumatic cushioning within the helmet and so constructed that the expansion thereof will be against or toward the walls of the helmet to provide an efficient shock 15 absorbing means for the head of the wearer and when inflated will not interfere or bind the head of the wearer.

A further object of this invention is the provision of means whereby complete and 20 thorough ventilation may be had to the head of the wearer, without destroying the cushioning effect of the device.

25 A still further object of this invention is the provision of a helmet of the above stated character which will be simple, durable and efficient and which may be manufactured and sold at a comparatively low cost.

With these and other objects in view as will 30 become more apparent as the description proceeds, this invention consists in certain novel features of construction, combination and arrangement of parts, as will hereinafter be more fully described and claimed.

For a complete understanding of my 35 invention, reference is to be had to the accompanying drawings and following description, in which

Figure 1 is a side elevation illustrating a 40 helmet constructed in accordance with my invention.

Figure 2 is a top plan view illustrating the same.

Figure 3 is a sectional view taken on the line 3-3 of Figure 2.

5 Figure 4 is a horizontal sectional view taken on the line 4-4 of Figure 3.

Referring in detail to the drawings, the numeral 1 indicates an outer casing constructed from leather or any other material suitable for the purpose and the crown portion

is provided with a series of ventilating openings 3. The casing 1 extends over the top of the head, forehead, base of the skull and ears of the wearer and is secured upon the head by a suitable adjustable chin strap 4. 55

An inner lining 5 is positioned within the outer casing 1 and has its edges stitched or otherwise secured to the outer casing for the purpose of forming a chamber within the helmet to receive an inflatable bag or 60

bladder 6 constructed from rubber or any other material suitable for the purpose and is provided with an inflated valve 7 located in one of the side portions or ear flaps of the helmet whereby air pressure may be introduced into the bladder or bag 6 as desired for the purpose of providing a pneumatic cushion. The inner wall or the wall 65

opposite to the wall engaging the outer casing 1 is of considerable thickness so that the 70 expansion of the bladder or bag when under air pressure will be toward or against the inner face of the outer casing 1. The bag or bladder is provided with ventilating openings aligning with the openings 3 and the 75 inner lining is stitched or otherwise secured as shown at 8 to the inner wall of the outer casing 1 about the openings 3 as clearly shown in Figure 3. Thus it will be seen that air 80 may freely circulate into and out of the helmet and the circulation will not be interfered with by the bag or bladder 6.

The side portions or ear flaps of the helmet are provided with a plurality of ventilating 85 openings 9 closed by wire mesh or similar material 10 and it is to be understood that the portion of the bag or bladder associated with the flaps is provided with ventilating openings aligning with the openings 9. The 90 openings 9 besides providing for ventilation also permit the wearer to readily hear when the device is placed over the head and ears.

A head engaging member 11 is secured to the inner lining 5 and comprises straps 12 95 arranged at right angles to each other with the ends secured in place so that the straps fit over the crown of the head and support the helmet thereon and in a slight spaced relation thereto. A forehead strap constructed 100

from sponge rubber or the like as shown at 13 is associated with the straps 12 and is adapted to engage about the forehead of the wearer to protect that portion of the head 5 as well as aiding in securing the device in place on the head.

The inner lining 5 may be constructed from a light weight leather or other material suitable for the purpose, therefore it will 10 be seen that a device has been provided which will be extremely light in weight and will provide an efficient protector for the head of the wearer as the bag or bladder when inflated to a desired air pressure will effectively absorb shocks and jars and prevent them from 15 being transmitted to the head of the wearer.

While I have shown and described the preferred embodiment of my invention, it will be understood that minor changes in construction, combination and arrangement of 200 parts may be made without departing from the spirit and scope as claimed.

Having thus described my invention, what I claim is:

256 A helmet comprising an outer casing; an inner casing secured in the outer casing to provide a chamber; a pneumatic cushioning bag in said chamber and having the inner walls of greater thickness than the outer 300 walls for the purpose of causing the expansion of the bag toward and against the outer casing, and a head engaging member secured to the inner casing.

In testimony whereof I affix my signature.

EDWARD J. FORD.
